ATTORNEY

UNITED STATES PATENT OFFICE.

JOSEPH WALTER, OF NEW YORK, N. Y.

SPEAKING-TUBE ANNUNCIATOR.

SPECIFICATION forming part of Letters Patent No. 294,535, dated March 4, 1884.

Application filed January 22, 1884. (No model.)

To all whom it may concern:

Be it known that I, JOSEPH WALTER, of the city, county, and State of New York, have invented certain new and useful Improvements 5 in Speaking-Tube Annunciators, of which the following is a specification.

This invention has reference to certain improvements in speaking-tube annunciators for which Letters Patent have been granted to me 10 heretofore under date of September 26, 1882, No. 264,977, the improvements being designed with a view to simplify the construction of the annunciator and render the same cheaper and more effective.

15 The invention consists of a speaking-tube annunciator, the S-shaped main tube of which is provided with a mouth-piece at one end and a valve at the other enlarged end, said valve being provided with an exterior striker that 20 rings a bell or gong attached to the main tube whenever an air-wave is passed through the speaking-tube from the farther end of the same. The striker operates by a fixed arm a pivoted indicator, the position of which indicates 25 whenever a signal has been given.

In the accompanying drawings, Figure 1 represents a rear elevation of my improved speaking-tube annunciator; Fig. 2, a side view, and Fig. 3 a vertical longitudinal section, of 30 the same.

Similar letters of reference indicate corresponding parts.

A in the drawings represents the S-shaped main tube of my improved annunciator, which 35 is provided at one end with a mouth-piece, A'. At the opposite end of the main tube A is arranged a valve, B, which, when at rest, does not close the entire orifice of the main tube A, but leaves an opening, b, below the valve of 40 sufficient size to permit communication through the speaking-tube in the direction of the arrow, Fig. 3. For this purpose that part of the tube A below the valve B is enlarged near the opening. The pivot d of the valve B is extended 45 laterally through the side wall of the tube A, and provided at its outer end with a striker, C, the laterally-bent front end of which is provided with a hammer that strikes a bell or gong, D, that is applied to the front wall of 50 the tube A. The striker C is stopped in one direction by the enlargement A² at the lower

end of the tube A, said enlargement furnishing the required space by which communication is established below the valve. The striker C is stopped in the other direction by an inwardly-projecting stop-pin, a, which projects into the path of the valve, the position of the pin a being such that the hammer strikes the gong when the valve B has attained a sufficient impulse from the air-wave. The valve B in 55 striking against the stop-pin a acts in the nature of a spring and causes the striker to rebound, so as not to stick to the gong by the air-pressure, which would dull the sound of the gong. The front wall of the tube A is concentric to the pivot of the valve B, so that the latter closes the speaking-tube when it has passed the enlargement A², so that the striker is thrown up against the bell. The bell D is supported on a bent post, D', that is secured to one of the 60 side walls of the tube A.

When communication is desired to be established through the speaking-tube, a wave of air is blown into the mouth-piece through the conducting-tube, the air-wave traveling through 65 the speaking-tube until arriving at the opposite end, where it impinges upon the valve B and throws the same suddenly from its vertical pendent position into an inclined position, as shown in dotted line in Fig. 3, so that its hammer strikes the bell. By blowing several times 70 in succession into the speaking-tube, these air-waves are repeated, and thereby the gong struck quickly in succession, whereby a signal 75 is given at the opposite end of the tube, and thereby attention drawn to the fact that communication is desired. Owing to the concentric shape of the tube A, a very light air-wave causes the valve B to oscillate beyond and above the enlargement A². The striker C lifts by a fixed 80 arm, e, a pivoted indicator, E, and throws it up on an inclined stop on rest e' at the side of the tube, as shown in dotted lines in Fig. 2. This position of the indicator shows that a call 85 has been made, even if the gong-signal has not been heard. After the party has communicated through the speaking-tube the indicator is thrown back in its former position, so as to be ready for the next signal. As an annunciator is arranged at each end of the speaking-tube, the alarm can be given from either end. 90 The annunciator may also be arranged in 100

inverted position to that shown in Fig. 1, in which case the valve has to be balanced by a counter-weight applied to its pivot, but in opposite direction to its striker, the counter-
5 weight holding the valve in vertical position until the same is tilted by the force of the air-wave passing through the speaking-tube to the annunciator.

Having thus described my invention, I claim
10 as new and desire to secure by Letters Patent—

1. In an annunciator for speaking-tubes, the combination of a main tube having an enlargement at one end, a valve pivoted to the enlarged end, said valve being smaller than its enlarged
15 end, a striker, C, attached to the outer end of the valve-pivot, and a gong secured to the main tube A, substantially as set forth.

2. The combination of a tube, A, having a mouth-piece, A', at one end and an enlargement, A², at the other end, a valve, B, pivoted
20

to the enlarged end, an exterior striker, C, attached to the pivot of the valve, a gong, D, attached to the tube A, and means whereby the striker C is stopped in either direction, substantially as specified.

3. The combination, with a main tube, A, having a mouth-piece, A', at one end and an enlargement, A², at its opposite end, a valve, B, pivoted to the enlarged end, a striker, C, attached to the pivot of the valve, a gong, D,
30 secured to the tube A, a pivoted indicator, E, operated by the striker, and a stop or rest, e', for the indicator, substantially as set forth.

In testimony that I claim the foregoing as my invention I have signed my name in presence of two subscribing witnesses.

JOSEPH WALTER.
